[57] CLAIM

The ornamental design for a vehicle body, as shown and described.

DESCRIPTION

FIG. 1 is a front perspective view of a vehicle body constructed in accordance to the teachings of a first embodiment of the present invention, it being understood that the hidden line showing throughout the drawings is for illustrative purposes only and accordingly forms no part of the subject invention;

FIG. 2 is a rear perspective view of the vehicle body shown in FIG. 1;

FIG. 3 is a side view of the vehicle body shown in FIG. 1, it being understood that the opposite side to that shown is a substantial mirror image thereof;

FIG. 4 is an elevated front view of the vehicle body shown in FIG. 1;

FIG. 5 is a front view of the vehicle body shown in FIG. 1; and,

FIG. 6 is a rear view of the vehicle body shown in FIG. 1.
